TO FOAMITE FIREFOAM COMPANY, OF NEW YORK, N. Y., A CORPORATION OF
DELAWARE.

FIRE-EXTINGUISHING SYSTEM.

1,403,621.

Specification of Letters Patent. Patented Jan. 17, 1922.

Application filed March 13, 1917. Serial No. 154,471.

To all whom it may concern:

Be it known that DUNCAN W. PATTERSON, a citizen of the United States, residing at New York city, in the county of New York and State of New York, has invented certain new and useful Improvements in Fire-Extinguishing Systems, of which the following is a specification.

This invention relates to fire extinguishing systems and more particularly to systems adapted to afford protection at different points or stations.

Various forms of sprinkler systems have heretofore been provided, these systems generally carrying a supply of water under pressure, spraying nozzles being located at desired points with the nozzles normally held inoperative by suitable means, such as fusible material. When a fire occurs at any point, the protecting fuse is melted, rendering the nozzle or nozzles active to deliver the water to the fire.

While these systems may prove efficacious where installed in a building or where the water supply is plentiful and operatively inexpensive, results are less favorable where the points to be protected are considerably scattered, thus placing a considerable supply of extinguishing medium in the system of piping, draining of which under fire conditions may prove a serious factor, especially where fires break out at different points, due to the fact that the systems generally have the pipes in open communication throughout the system. Moreover, systems employing water as an extinguishing medium are incapable of use where the point to be protected is of an inflammable nature, as for instance, tanks carrying oil, gasoline or other inflammable substances.

A recently developed process of extinguishing fires—a foam-extinguishing process—is effective in protecting tanks of this character. In this process, two liquids are normally kept separate, one or both of the liquids carrying a foam-forming material which becomes active only when the liquids are combined, or brought together to produce the extinguishing medium adjacent the point of application. One form of such composition is disclosed in the patent to Walker, No. 1,116,090, in which the liquids used are a solution of bi-carbonate of soda

with "foamite," and a solution of aluminum sulphate. By bringing these solutions together at the proper point, a gas is formed and practically kept in extinguishing position by the foam which acts as a deterrent against the escape of the gas.

A simple form of apparatus for placing this process into use in connection with oil or other tanks, is shown in the patents to Walker, Nos. 1,186,249 and 1,186,251, the latter disclosing a preferred form of mixing head which can be readily applied to a tank.

The most efficient operation of the process is had when the several solutions are kept separate until the mixing chamber is reached, thus eliminating difficulties which may be had in carrying the mixed solution, with the foam active, through a pipe or conduit of any considerable length. An efficient solution of this difficulty is disclosed in Patent No. 1,186,249, but such apparatus is more particularly adapted for single and isolated tanks, each installation having its individual source of supply.

This form of installation may, of course, be employed where a plurality of tanks are positioned in proximity to one another, but this involves the use of containers for the individual supplies—necessitating considerable installation and maintenance work—or the use of a piping system from a single supply, and in which the pipe connections leading to the various valves would be maintained filled with the solution, a condition somewhat analogous to the sprinkler systems heretofore referred to. Should the installation be of the single supply type, it would require the maintenance of each solution in proper working condition throughout the piping system, a difficult matter where pipe lines are of relatively small cross-section or are of considerable length, so that draining action either by actual fire extinguishing use or for renewal purposes, would be required at more or less frequent intervals, a condition which is not present in connection with sprinkler systems employing water.

An additional disadvantage is the fact that the distributing pipes should be buried in order to avoid danger of freezing, thus increasing the difficulties of draining and cleaning.

The present invention meets these condi-

tions by employing a single supply station with distributing connections leading to the several tanks but normally maintained free from the solution, the latter being delivered 5 to the distributing connection or connections when the fire requires the delivery of the solution and the protection afforded by the extinguishing composition. Since the control devices are located at the tanks (practically 10 at the end of a connection) suitable means are employed to begin the distribution at the time when the control device (generally a fusible element) becomes active.

In the present embodiment of the invention, the means employed is in the form of 15 compressed air, the distributing system carrying the air at an approximately constant pressure, the activity of the control device acting to affect this pressure and thereby 20 start the solution supply mechanism into operation.

In addition, the invention contemplates the delivery of the solution solely to the point where needed, thereby restricting the 25 amount of solution delivered to the system and decreasing the amount of drainage required to restore normal conditions, with a consequent decrease in the cost of maintenance.

30 The invention also contemplates control of the supply of extinguishing material to extinguishing systems by differentiating pressures to enable the extinguishing medium to be normally maintained out of the distributing system and made active therein to bring the medium to the point of application as needed.

To these and other ends, the nature of 40 which will be readily understood as the invention is hereinafter disclosed, said invention consists in the improved construction and combination of parts, together with the improved methods indicated, all as herein-after fully described, illustrated in the accompanying drawings and more particularly 45 pointed out in the appended claims.

In the accompanying drawings in which similar reference characters indicate similar parts in each of the views,—

50 Figure 1 is a schematic view showing a general form in which my present invention may be provided.

Figure 2 is a view, partly in section and partly in elevation showing portions of the 55 system of Fig. 1.

Figure 3 is a diagrammatic view, showing in side elevation one form of installation on a tank.

Figure 4 is a top plan view of parts shown 60 in Fig. 3.

Figs. 5 and 6 are sectional views of two different valve constructions which may be employed.

Figs. 7 and 8 are detail views showing a

different way of connecting the system to 65 the tank.

Figure 9 is a sectional view of a valve structure which may be employed.

While the general principles of the present invention are adapted for use with single 70 tanks, the invention is designed more particularly to meet conditions which are present where a number of tanks are so located as to permit each being served from a single point by the use of pipe connections between 75 a supply-station and the individual tanks, thereby enabling a supply to be kept at a single point and readily maintained in proper condition for service.

As heretofore pointed out, the system is so 80 preferably of a type adapted to operate under foam-extinguishing practice, and hence employing a plurality of solutions, normally separated but brought together and combined to produce the extinguishing medium. Efficient 85 service practically necessitates retaining the solutions separate until they reach the vicinity of the fire and as the solutions are each of a form which may be affected to a more or less extent when in a quiet 90 state, it is desirable to keep them out of the connections so far as is possible until actual service conditions require the delivery of the solutions to the point of application—the fire.

One way of meeting this condition is pointed out in Patent No. 1,186,249 heretofore referred to and in which the solutions are kept separate in tanks and under compressed air pressure of a desired value, the 100 connections being closed by valves at points close to the solution tanks with the valves normally closed. When a fire occurs, a trip mechanism is made active to open the valves, whereupon the solution, under the action of 105 the pressures within the solution tanks, are brought to a mixing chamber through which the extinguishing medium is delivered to the point of application. In this form of apparatus, the solutions are maintained under an 110 approximately constant pressure.

In the present invention, the delivery of the solution is provided by a suitable pump mechanism which is normally inactive but rendered active when the trip mechanism 115 is made active, such trip activity setting in motion control mechanism operative on the pump prime mover, whereupon the pump mechanism acts to pump the solutions into the connections and forces the solutions to 120 the mixing chamber. As it is desirable in order to prevent freezing as well as the corrosive action of acid mixtures, that the connections be of the dry pipe type, such connections are filled with a filling medium 125 adapted to produce this result, a preferable medium being compressed air maintained at a substantially constant pressure while

the system is inactive. Through suitable controlling devices this air is also made effective to control the beginning of the solution pump mechanism activities, the latter bringing the solution into the connections to take the place of the compressed air, the pumping pressure being greater than the compressed air pressure.

This general operation is applicable for use in installations for single tanks or for a plurality of tanks and will be readily understood by a brief reference to Figure 1, assuming the mixing chamber at station A is properly located with respect to a tank 15 to be protected, the connections leading to this chamber being those considered in the explanation.

20 and 21 designate respectively two tanks for receiving the two liquid solutions, one 20 of the solutions containing "foamite" referred to in the earlier patents above enumerated.

22 indicates a main header pipe connected to tank 20 by connection 22^a and to the 25 controlling mechanism at station A by sub-header pipe 23. 24, 24^a and 25 designate the similar structures connecting tank 21 with such controlling mechanism.

26, 26 designate check valves which join 30 connections 22^a and 24^a with their respective headers, these valves being normally closed by the pressures within the header system. Suitable gate valves 27 may be located 35 within connections 22^a and 24^a to enable the tanks to be manually closed from the system when desired.

While the main and sub-header pipes are shown as separate and of different diameters (to meet other conditions presently referred 40 to) it is to be understood that in installations for single tanks these pipes may be continuous and of the same diameter.

In the form shown in Fig. 2, the pipes 23 and 25 are led to an automatic valve 28 for 45 each pipe; in the form shown in Figs. 7 and 8 these pipes lead to a valve structure common to said pipes, as presently described.

Valves 28 are each connected to the lower end of a mixing chamber X which may be 50 and preferably is of the type shown in Patent No. 1,136,251, said chamber being suitably mounted on the tank which is being protected, and which is indicated at 29. The connections between pipes 23 and 25 and the 55 mixing chamber are normally closed by valves 28. Valves 28 may be of any type suitable for the purpose, the drawing indicating a well known structure having a diaphragm chamber 28^a in which is mounted a diaphragm 28^b serving to control the movements of the valve to and from its seat. A suitable vent 28^c connects the sub-header pipe with the outer portion of the diaphragm chamber 28^a, this vent being controlled at its outer end by suitable means

which acts in the nature of a check valve. Leading from chamber 28^a of each valve is a pipe 30, of small diameter, said pipes being joined, by a T-connection with a pipe 31 the outer end of which is preferably provided 70 with a suitable control device 32, such for instance, as a thermal control, which normally maintains the outer end of pipe 31 closed, but which, in the presence of fire is operated to open such outlet. Obviously, 75 device 31 is located at such point as will enable fire conditions to quickly render it active, as for instance in proximity to the surface of the contents of tank 29; for convenience pipe 31 may extend through the discharge outlet of the mixing chamber, pipes 30 being joined thereto within such chamber.

In the form shown in the drawings, the various pipe lines of the system are of proper relative diameters. For instance, headers 85 23 and 25 may be 2½" in diameter; pipes 30 and 31, 1½" in diameter, and vent 28^c may be 1" in diameter, headers 22 and 24 being of suitable diameter. It will be understood of course that these diameters are simply 90 illustrative.

33 designates a solution pump mechanism which includes prime mover 33^a, and pumps 33^b mounted to operate in header pipes 22 and 24, these pumps being of a suitable type 95 and each adapted to afford open communication between the header pipes on opposite sides of the pump.

With the control device 32 closed, the entire system (with the exception of the solution tanks and connections 22^a and 24^a) is maintained under an approximately constant air pressure, such for instance as 50#. This is provided by the operations of an air compressor 34 of suitable construction, the 105 prime mover of which is automatically controlled by a suitable automatic governor 35, which (as indicated in Fig. 9) may be of the diaphragm type, the valve being set to maintain the desired pressure in the system. Air compressor 34 is connected with pipes 22 and 24 on the suction side of the pumps by pipes 36 and 36^a, this connection being controlled by one or more check valves 37. Pipes 36 and 36^a are of suitable diameter—110 for instance ¾"—to enable the system to be rapidly filled with the air, as when starting up the system or in filling the lines after a fire. To maintain the pressure and take care of leakage, a pipe line of smaller diameter—for instance 1" —may be employed, this line being indicated as a pipe 38^a connecting pipe 36 with a pipe 38, pipe 38^a carrying a check valve 39. Pipe 38 is connected to an automatic governor 40 (which 125 may be similar in structure to the valve of Fig. 9) which operates to control the prime mover of the solution pump and is preferably set so as to start pumping of the solution under pressure conditions lower than 130

the normal pressures in the system; for instance, this operating pressure may be at 25#. Automatic governor 35 is connected with pipes 23 and 24 on the discharge side 5 of the pumps by pipes 41.

The operation of the parts referred to is substantially as follows:

Control device 32 being closed and the pressure within the system reduced, as when 10 the system is being placed in operation, and with the solution pump held inactive, the reduced pressure within the system causes automatic governor 35 to start operation of the air compressor, which operation delivers 15 the air to pipes 22 and 24 passing through the pumps 33^b and into pipes 23 and 25, through vents 28^c to chambers 28^a and into pipes 30 and 31, the pressures building up until the desired pressure is reached, where- 20 upon governor 35 is closed by the pressures within pipes 41. This places the entire system under such pressure as is provided in connection with valve 35. Minor reductions in pressure, as by leakage, etc., are 25 made effective on governor 35 through pipes 41, causing the compressor to operate and deliver air to the several lines and restore the pressure. Preferably this maintenance of pressure is made through the lines indicated as 38 and 38^a and for this purpose 30 pipes 36 and 36^a are provided with gate valves 36^b which are preferably closed by the operator after the rapid-filling operation has been completed.

35 This line, (36, 38^a and 38) is not only sufficient to take care of these minor conditions, but is in direct connection with automatic governor 40, and also enables check valve 39 to become active in closing line 36 40 under rapid pressure reduction, thus maintaining the pressures within pipes 36 and 36^a above the pressures at which the pumps are to operate.

When the outlet end of pipe 31 is unsealed 45 by control device 32, as in the presence of a fire in tank 29 the lines leading from chambers 28^a open to the pressure of tank 29 (practically atmospheric pressure) quickly reducing the pressure within chambers 28^a, 50 since vents 28^c are incapable of maintaining the pressures within these chambers under these conditions.

As the pressure in chambers 28^a is thus 55 made much less than that opposing valves 28, such valves will open, thus opening communication between pipes 23 and 25 and the mixing chamber, thereby opening the header lines and rapidly reducing the pressures therein, the compressor being unable to meet 60 this condition by reason of the small supply through line 38. As a result, governor 40 will be rendered active to start the solution pump (designed to provide a greatly increased pressure—for instance 200#) thus 65 creating a suction effect in lines 22^a and 24^a,

opening check valves 26 and drawing the solutions from tanks 20 and 21, and at the same time forcing these solutions through the various lines to the mixing chamber, where the solutions combine to produce the extinguishing medium, the latter passing through the mixing chamber outlet to the point of application. 70

Owing to the large pressure decrease, check valve 39 will close, thus preventing 75 the solution from reaching lines 36 and 36^a; this increase will also be effective on governor 35 to prevent compressor operation. Similarly valves 28 will move to close vents 28^c against pressure of the solution, thus 80 preventing access of solution to diaphragm chambers 28^a.

As will be seen, this arrangement provides for normally maintaining the connections between the solution tanks and the point of application filled with a fluid which is of a different character from that which constitutes the extinguishing medium, thus eliminating liability of the connections being affected by the ingredients of the extinguishing medium. The arrangement also provides for maintaining this fluid under a pressure greater than that of atmospheric pressure but less than the pressure at which the extinguishing medium operates, thus 90 ensuring rapid movement of the fluid (air) when the control device unseals the system and provides a release of pressure which is effective in starting the solution pump, the latter producing pressures greater than the 100 fluid pressure, thereby ensuring that the connections will be quickly cleared of the air and carry the solutions. 95

Under this arrangement the solution tanks normally need not be under pressure, the 105 solutions being pumped therefrom instead of being forced by the action of compressed air.

While more than a single tank may be connected to the system thus described and will provide the desired fire extinguishing action 110 at the point of application, it is preferred to amplify the control features under such conditions, since it may not be desirable to have each sub-header line of the system subjected to the air-draining operation whenever fire 115 occurs at a single tank—an operation which would provide substitution of the solution for the air which is drained and force the solution into all of the header lines, necessitating an excessive cleaning action at the end 120 of the extinguishing operation.

To meet these conditions I prefer to limit the air-draining action to the main header line and such sub header line as may lead to the point of application, the remaining sub-header lines thus being kept free from the solution. This not only restricts the amount of cleaning necessary but in addition requires the use of a lesser amount of solution 125 to fill the active portion of the system. 130

While this control may be provided in various ways I prefer to produce the result by an automatic selective control by means of which the various sub-header lines are 5 normally in open communication with the main header line, thus bringing each of such sub-header lines under the compressed air pressure and its control, this condition being automatically changed in those sub-header lines which are to remain inactive, by maintaining the pressures in the inactive lines unchanged. This selective action is controlled by the differences in pressure between the compressed air pressure and the pressure at 15 which the solution is carried through the system. One form of mechanism for producing this result is as follows:

Mounted in each sub-header pipe is a valve 42 which normally closes the main passageway through the pipe. Valve 42 is normally held seated by a diaphragm 43 of greater diameter than that of the valve, air chamber 43^a serving this purpose. Chamber 43^a is connected to the header pipe on opposite 25 sides of valve 42, by connections 44 and 44^a, connection 44 carrying a differentiating valve 45, connection 44^a carrying a differentiating valve 46.

Valves 45 and 46 are shown more particularly in Figs. 5 and 6, these valves each carrying a valve chamber 47 within which is mounted a spherical valve 48, formed of suitable material, such, for instance, as wood covered with rubber, or a floating copper ball, enabling the ball to float in the presence of liquid. The upper end of each chamber 47 is formed with a seat 48^a for valve 48; the lower end of the chamber is of different form in the two valves. Valve 45 has the lower 35 end of the chamber formed with a seat 48^b complementary to the ball valve, but the passageway leading to this seat is restricted by a diaphragm 45^a having a single port which may, for instance, have a diameter of 45 1/16". Valve 46 has the lower end of chamber 47 formed with a seat 46^a which, however, is not continuous, ports 46^b providing open communication past the seated valve, the port area being considerably greater than 50 that of port 45^b—for instance, the port area may equal that of a 1/4" pipe, the connections 44 and 44^a—which practically form a bypass—being of this diameter.

The differentiating valve system (valves 55 42 and differentiating valves 45 and 46) are preferably located adjacent the point of connection of main header pipes and sub-header pipes, thus closing practically all of the sub-header line to the main header line by 60 valves 42.

With these additional features in service, it will be clear that during filling of the system with air, valves 48 will not prevent the passage of air into the sub-header pipes to 65 permit the proper pressures to be obtained at

the delivery end, the result being that the system gradually reaches the pressure at which the air is to operate.

When control device 32 at any one of the tanks 39 is made active to unseal the end of pipe 31, the action heretofore referred to takes place in diaphragm chamber 28^a with which the pipe is connected, thus permitting valves 28 to open and permit the air in the sub-header line in which these valves 28 are 70 located to pass into the mixing chamber, resulting in a rapid fall of pressure in this line. This reduction in pressure acts to open valve 42 of the header line through the reduction in pressure within chamber 43^a 80 caused by the inability of port 45^b to supply the amount of air which is discharging through ports 46^b (due to difference in cross-sectional area of the ports.) The greater pressure on the seated valves (open to the 85 main header line pressure) causes valves 42 of the selected line to be opened and bring the main header line and sub-header line into full communication, followed by the automatic starting of the solution pumps, 90 etc., as previously described.

While this action takes place in the desired sub-header line, the remaining sub-header lines not only remain inactive but are also maintained free from the solution. 95 When the pressure in the main header line is reduced, ball 48 of valve 45 of the inactive lines will immediately seat at the bottom of the valve chamber, thus retaining the pressure in chamber 43^a and holding valve 42 100 closed. Consequently, each sub-header system beyond ball 48 is kept at the normal pressure. When the high pressure of the solution becomes effective in the main header line, each ball 48 of valves 45 will move (as 105 by floating) to its upper seat thus preventing the excess pressure to be placed on the sub-header line, and at the same time preventing solution from reaching chamber 43^a. This protection of chamber 43^a in the active 110 sub-header line is obtained by reason of the fact that the ball 48 of each of valves 45 and 46 passes to its top seat, closing the connections to the chamber against pressure to seat valve 42 and preventing entrance of solution. 115

It is to be understood, of course, that valves 42 will be so proportioned that the pressures within chambers 43^a will be sufficient to maintain the valve closed against 120 the much greater pressure of the solution.

Should either of the remaining tanks catch fire, its control device 32 will be made effective, thus setting in motion the several control operations leading to the opening 125 of valves 42 of the sub-header line, and since the solution has been brought to that valve by the previous operation no time is lost in placing the solutions in the mixing chamber and thus on to the fire. In each instance, 130

however, it is necessary that control device 32 be made active before delivery of solutions to the mixing chamber will be had, so that all sub-header lines in which the seal of 5 the control device remains intact, not only are kept from receiving the solution, but the air pressure in these lines is maintained, able to take care of a second fire. This eliminates necessity of cleaning the unused sub-header 10 lines, and at the same time dispenses with the necessity for again building up the air pressure within these unused lines.

This arrangement permits of the use of 15 any desired number of sub-header lines, it being understood, of course, that the main header line will have a capacity sufficient to take care of conditions where a number of fires occur concurrently.

As heretofore pointed out, the "automatic 20 foamite valve" may have different forms—one form is indicated at 28. In Figs. 7 and 8 another way of providing the result is shown. In this form, sub-header lines 23 and 25 are connected directly to the lower 25 ends of the mixing chamber, the outlet ends being normally closed in suitable manner, as by the use of caps 50 held in position by suitable means, as for instance a toggle-like structure 51 located between the caps—the 30 outlets to lines 23 and 25 opposing each other. Structure 51 is normally maintained active by a weight 52 located in the tank and connected to structure 51, the connections including suitable trip mechanism, as for instance one or more fusible links 53. Or the 35 mechanism may be tripped by hand by manipulating cord 51^a.

When fire is present in the tank, the trip 40 will become active to release the weight or cords 51^a will be manipulated, thus releasing caps 50 from restraint and subject to the header pressure. The header outlets will thus be opened, reducing pressure in the sub-header line and setting in motion the 45 remaining operations as before described.

Obviously this general arrangement may be 40 considered as a mechanical equivalent of the similar structure which includes valves 28.

This form eliminates the use of valves 28 50 by a less expensive arrangement, and at the same time offers the advantage of having the streams enter the chamber in opposed directions and meeting within the chamber producing a rapid commixing of the solutions. 55 This latter type is not specifically claimed herein as it pertains to subjects-matter of an application of Frank A. Epps, Patent No. 1,296,937, of which I am aware, the form shown in Figs. 7 and 8 being one of the several forms shown in that application suitable for use in the present invention.

Likewise, the specific structure of Fig. 9 60 is not claimed herein, such structure being one form of a regulating valve adapted to 65 act as a governor. In this form a valve 60

controls the passage from the supply to the prime mover. 61 indicates a spring tending to open the valve, and 62 a piston open to the pressure line, the pressure operating the piston in a direction to close the valve. For 70 instance, the piston for governor 35 is subject to the pressure in pipes 41. If the governor is set at 50 pounds the valve will seat at substantially such pressure. If the pressure in pipes 41 is reduced, tension of spring 75 61 will predominate and the valve opens. When diaphragm pressure predominates, the valve will close.

In connection with governor 40, pipe 38 provides the control, this governor being so preferably set at a lower operating pressure.

Obviously, hand control, as by throttle valves, may be additionally employed, if desired.

Obviously, more or less manual control of 85 the apparatus may be provided by the use of hand-operated valves. For instance, each sub-header line may have gate valves 27^a to provide for hand control, these valves being left open for automatic operation. Or each 90 differential system may have such control by the use of valves 70, closing of which prevents automatic action of the differential valves.

I also preferably employ suitable relief 95 valves 71 to permit flexibility of apparatus operations.

As will be understood, closing of valves 27 to close the supply of the solutions will effect a pressure reduction in the header lines 100 sufficient to render governor 35 active, thus introducing air on the suction side of the pumps, the valves of the latter permitting the air to pass therethrough to the discharge side of the pumps. If valves 36^b are also 105 opened, the entire air pressure may become active to aid in clearing the header lines from solution by blowing it out through the open ends of the connections. In this manner cleaning may be had to a more or less 110 extent. By then closing the throttle valves of the prime movers of the pump and compressor, further cleaning action, if necessary, may be had, the open ends of the lines restored by applying trip mechanism, the 115 compressor made active, valves 27 opened, and the system placed in full operative condition by closing valves 36^b.

The system is simple in construction and 120 operation, many of the valves, etc., being articles of general commerce. The installation can therefore be produced at a comparatively low cost, and as the solutions are maintained in tanks until required, the cost of maintenance and of attendance is reduced 125 to a minimum.

While I have herein shown and described 130 several ways in which my invention may be carried into effect and uses to which it may be put, it is to be understood that variations

and modifications therein may be required to meet the exigencies of individual installations. I therefore desire to be understood as reserving the right to make any and all such changes or modifications as may be found desirable or necessary, insofar as the same may fall within the spirit and scope of the invention as expressed in the accompanying claims. And nothing herein is in-

- 10 tended as limiting the scope of the invention to use with the particular solutions referred to, and the use of single pipe lines in which the extinguishing medium is carried to the point of application—the operation of but one of the pair of header pipes—
15 is contemplated where such use is in accord with the spirit and scope of the invention as claimed.

What I claim is—

- 20 1. In fire extinguishing systems of the two-solution type employing separate sources of supply one for each solution forming the fire extinguishing medium, each source being separately connected to a suitable mixing and delivery apparatus, the method of delivering the extinguishing medium through said apparatus which consists in normally maintaining the connections between the supply sources and said apparatus 25 filled with a fluid differing in character from such medium and under an approximately constant pressure greater than atmospheric pressure and less than the delivery pressure, with the medium at said 30 sources under a pressure less than that of the filling fluid and applying delivery pressure to the medium at said sources by the reduction of the fluid pressure in the presence of fire conditions to substitute the extinguishing 35 medium for the filling fluid for delivery of the same through said apparatus.

40 2. In fire extinguishing systems of the two-solution type comprising separate sources of supply one for each solution forming the fire extinguishing medium, apparatus for mixing said solutions and applying the product to the fire, separate connections between each of said sources and the apparatus, and mechanical means in said connections for 45 applying delivery pressure to the solutions, the method of delivering the extinguishing solutions from the sources to the point of application which consists in normally maintaining said connections filled with a 50 fluid differing in character from the solutions and under a pressure greater than atmospheric pressure and less than the delivery pressure, and rendering the delivery pressure active on the solutions by actuating 55 the mechanical pressure-producing means through reduction in pressure of the fluid in the presence of fire conditions whereby the solutions will be substituted for the fluid in 60 said connections.

65 3. In fire extinguishing systems of the two-

solution type employing separate sources of supply one for each solution forming the fire extinguishing medium, each source being separately connected to a suitable mixing and delivery apparatus, the method of delivering the extinguishing medium through said apparatus which consists in normally maintaining the connections between the supply sources and said apparatus filled with air under an approximately constant pressure greater than atmospheric pressure and less than the delivery pressure, with the solutions at said sources under a pressure less than that of the air and applying delivery pressure to the solutions at said sources by the reduction of the air pressure in the presence of fire conditions to substitute the extinguishing medium for the air for delivering the same through said apparatus.

4. In fire extinguishing systems of the two-solution type comprising separate sources of supply one for each solution forming the fire extinguishing medium, apparatus for mixing said solutions and applying the product to the fire, separate connections between each of said sources and apparatus, and mechanical means in said connections for applying delivery pressure to the solutions, the method of delivering the extinguishing medium from the sources to the point of application to the fire which consists in normally maintaining said connections filled with air under a pressure greater than atmospheric pressure and less than the delivery pressure, and rendering the delivery pressure active on the solutions by actuating the mechanical pressure-producing means through reduction in pressure of the air in the presence of fire conditions whereby the solutions will be substituted for the air in said connections. 105

5. In fire extinguishing systems of the foam-extinguishing type, the method of delivering the component solutions at the point of commixture which consists in normally maintaining the connections between the supply sources and the point of commixture filled with a fluid differing in character from the component solutions and under an approximately constant pressure greater than atmospheric pressure and less than the delivery pressure of the solutions, releasing such normal pressure at a delivery terminal under fire conditions, increasing the pressure of the component solutions upon the release of such normal pressure in the connections, and delivering the released fluid in streams opposing each other at such terminal, and delivering the solutions from such terminal in direct sequence to the delivery of the released fluid. 110 115 120 125

6. In fire extinguishing systems of the foam-extinguishing type, the method of delivering the component solutions at the point of commixture which consists in normally maintaining the connections between the 130

- supply sources and the point of commixture filled with a fluid differing in character from the component solutions and under an approximately constant pressure greater than 5 atmospheric pressure and less than the delivery pressure of the solutions, releasing such normal pressure at a delivery terminal under fire conditions, increasing the pressure of the component solutions upon the release 10 of such normal pressure in the connections, delivering the solutions to such terminal prior to commixture, and commixing the solutions by delivery from such terminal in opposed streams.
- 15 7. In fire extinguishing systems of the foam-extinguishing type, the method of delivering the component solutions to the point of comamixture which consists in normally maintaining the connections between the 20 supply source and the point of commixture filled with a fluid differing in character from the component solutions and under an approximately constant pressure greater than atmospheric pressure and less than the delivery 25 pressure of the solutions, normally storing the solutions individually under a pressure less than such normal fluid pressure, reducing the normal fluid pressure by the presence of fire conditions and concurrently 30 delivering the solutions to said connections and placing the solutions under delivery pressure to substitute said solutions for the filling fluid at the point of commixture.
- 35 8. In fire extinguishing systems adapted to operate at either of a plurality of separate points under fire conditions, the method of delivering the extinguishing medium from a common source of supply to that delivery 40 terminal active at the point of fire which method consists in normally maintaining a substantially uniform fluid pressure throughout the distributing connections, said pressure being of approximately constant predetermined 45 value intermediate the delivery and non-delivery pressure values of the medium supply, reducing the normal pressure within that portion of the distributing connections leading from the source to the point 50 of application selected by fire conditions and concurrently introducing and distributing the medium into and through the selected connections to such point of application.
- 55 9. In fire extinguishing systems adapted to operate at either of a plurality of separate points under fire conditions, the method of delivering the extinguishing medium from a common source of supply to that delivery 60 terminal active at the point of fire, which method consists in filling the distributing system with a fluid of a character differing from the medium and normally maintaining a substantially uniform and approximately constant predetermined pressure of such 65 fluid throughout the connections of such sys- tem with the fluid pressure having a value intermediate the pressure values of the delivery and non-delivery pressures of the medium supply, reducing the normal pressure within that portion of the distributing connections leading from the source to the point of application selected by fire conditions and concurrently introducing and distributing the medium into and through the selected connections to substitute the medium for the fluid in such connections and at the point of application. 70
10. In fire extinguishing systems adapted to operate at either of a plurality of separate points under fire conditions, the method of delivering the extinguishing medium from a common source of supply to that delivery terminal active at the point of fire, which method consists in normally maintaining a substantially uniform fluid pressure throughout the distributing connections, said pressure being of approximately constant predetermined value not less than the non-delivery pressure of the medium supply and less than the delivery pressure of the extinguishing medium, reducing the normal pressure within that portion of the distributing connections leading from the source to the point of application selected by fire conditions and concurrently introducing and distributing the medium into and through the selected connections to such point of application while maintaining the normal pressure in the unselected connections. 85
11. In fire extinguishing systems adapted to operate at either of a plurality of separate points under fire conditions, the method of delivering the extinguishing medium from a common source of supply to that delivery terminal active at the point of fire, which method consists in normally maintaining a substantially uniform fluid pressure throughout the distributing connections, said pressure being of approximately constant predetermined value intermediate the delivery and non-delivery pressure values of the medium supply, reducing the normal pressure within that portion of the distributing connections leading from the source to the point of application selected by fire conditions while maintaining the pressure conditions within the remainder of the connections and concurrently introducing and distributing the medium into and through the selected connections to such point of application. 100
12. In fire extinguishing systems of the two-solution type, separate storage sources one for each solution, normally maintained under non-delivery pressure, connections between each source and a delivery terminal means operatively related to the connections for each of said solutions for delivering said solutions to the terminal under fire conditions, fluid pressure means in each of said connections for maintaining the connec- 125 130

tions normally free from the solutions, unitary means for releasing said fluid pressure means in the presence of fire conditions, said solution-delivering means being rendered active by the release of the fluid pressure means.

13. In fire extinguishing systems of the two-solution type, a storage source for each solution, mixing and delivery apparatus, 10 separate connections between each of said sources and said apparatus, normally inactive pumping means operatively related to each of said connections adapted to pump each solution separately from its source to 15 said apparatus, fluid pressure means for normally maintaining said connections free from the solutions, and unitary means for releasing said fluid pressure means in the presence of fire conditions and actuating said 20 pumping means to deliver each solution through its connections to said apparatus.

14. In fire extinguishing systems of the two-solution type, a storage source for each solution, mixing and delivery apparatus, 25 separate connections between each of said sources and said apparatus, normally inactive pumping means operatively related to each of said connections adapted to pump each solution separately from its source to 30 said apparatus, said connections being normally filled with a fluid differing from the solutions, means for maintaining said fluid in the connections at a pressure greater than atmospheric pressure and greater than the 35 pressure of the solutions at their respective sources but less than the delivery pressure of said solutions produced by the pumping means, and unitary means for releasing said fluid from pressure and simultaneously 40 rendering active the pumping means to apply delivery pressure to the solutions substituting said solutions for the fluid in the connections and delivering the solutions to said apparatus.

45 15. In fire extinguishing systems of the foam extinguishing type and in combination, a source of supply for each of the solutions of the extinguishing medium, the solutions in said sources being normally maintained below delivery pressure, delivery headers adapted to deliver the several solutions to a delivery terminal at the point of application, means for normally maintaining said headers free from the solutions, normally inactive means including pumping mechanism rendered active in time of fire for providing delivery pressure to said solutions and for delivering the solutions to such terminal via the headers, and means 55 operative at such terminal under fire conditions for controlling the start of mechanism operation.

60 16. In fire extinguishing systems of the foam extinguishing type and in combination, 65 a source of supply for each of the solutions

of the extinguishing medium normally maintained under non-delivery pressure, connections between such sources and a normally inactive delivery terminal, means whereby said connections are normally maintained 70 free from such solutions in advance of fire conditions at such terminal, and means for producing the solution delivery pressure and for delivering the medium at such terminal in the presence of fire conditions, said last 75 mentioned means including a normally inactive pump mechanism rendered active in time of fire by the activity of the delivery terminal.

17. In fire extinguishing systems of the foam extinguishing type and in combination, a source of supply for each of the solutions of the extinguishing medium normally maintained under non-delivery pressure, 80 connections between such sources and a normally inactive delivery terminal, and means whereby said connections are normally maintained free from such solutions in advance of fire conditions at such terminal, said means including control mechanism at such 85 terminal adapted to normally maintain the terminal closed and to open the terminal in the presence of fire conditions, and a normally inactive means including pumping mechanism rendered active in time of fire 90 for providing delivery pressure to said solutions and for delivering the solutions to such terminal, the said mechanism having its activity controlled by the condition of such terminal.

100 18. In fire extinguishing systems of the foam extinguishing type and in combination, a source of supply for each of the solutions of the extinguishing medium normally maintained under non-delivery pressure, 105 connections between such sources and a normally inactive delivery terminal, means whereby said connections are normally maintained free from such solutions in advance of fire conditions at such terminal, means for producing the solution delivery pressure and for delivering the medium at such terminal in the presence of fire conditions, said last 110 mentioned means including a normally inactive pumping mechanism operative in said 115 connections and rendered active in time of fire, and means controlled by the condition of the delivery terminal for rendering said mechanism active.

120 19. In fire extinguishing systems and in combination, a source of supply for the extinguishing medium, connections between such source and a normally-inactive delivery terminal, means whereby said connections are normally maintained free from such medium in advance of fire conditions at such terminal and are rendered active for delivering the medium at such terminal in the presence of fire conditions, said means including mechanism for normally producing 125 130

a fluid pressure in said connections of sufficient value to prevent entrance of said medium thereinto, pressure-release means at such delivery terminal rendered active in the presence of fire conditions, and means for rendering said mechanism inactive during presence of the medium in the connections under normal fire protection conditions.

20. In fire extinguishing systems and in combination, a storage reservoir forming a source of supply for the extinguishing medium normally maintained under non-delivery pressure, connections between such source and a normally inactive delivery terminal, means whereby said connections are normally maintained free from such medium in advance of fire conditions at such terminal pump mechanism rendered active for delivering the medium at such terminal 20 only in the presence of fire conditions, said means including mechanism for supplying a predetermined fluid pressure to said connections, said fluid pressure being of less value than the delivery pressure of the medium, and means for controlling such supply to maintain such pressure substantially constant.

21. In fire extinguishing systems and in combination, a storage reservoir forming a source of supply for the extinguishing medium normally maintained under non-delivery pressure, means for applying delivery pressure to the extinguishing medium, connections between such source and a normally inactive delivery terminal, means whereby said connections are normally maintained free from such medium in advance of fire conditions at such terminal and rendered active for delivering the medium at such terminal in the presence of fire conditions, said means including mechanism for supplying a predetermined fluid pressure to said connections, said fluid pressure being of less value than the delivery pressure of the medium; means controlled by pressure variations in the connection for controlling such supply to maintain such pressure substantially constant, and means independent of the mechanism supplying fluid pressure to operate the means for applying the delivery pressure to the extinguishing medium under fire conditions.

22. In fire extinguishing systems and in combination, a source of supply for the extinguishing medium normally maintained under non-delivery pressure, connections between such source and a normally-inactive delivery terminal, means whereby said connections are normally maintained free from such medium in advance of fire conditions at such terminal and are rendered active for delivering the medium at such terminal in the presence of fire conditions, said means including air-compressing mechanism for supplying fluid pressure to said connections,

said fluid pressure being of less value than the delivery pressure of the medium, and means operative on the prime mover of said mechanism for controlling the mechanism operations to maintain a substantially constant pressure in said connections. 70

23. In fire extinguishing systems and in combination, a source of supply for the extinguishing medium normally maintained under non-delivery pressure, connections between such source and a normally-inactive delivery terminal, means whereby said connections are normally maintained free from such medium in advance of fire conditions at such terminal and are rendered active for delivering the medium at such terminal in the presence of fire conditions, said means including air-compressing mechanism for supplying fluid pressure to said connections, said fluid pressure being of less value than the delivery pressure of the medium, and means operative on the prime mover of said mechanism and controlled by pressure variations in the connections for controlling the mechanism operations to maintain a substantially constant pressure in said connections. 80

24. In fire extinguishing systems and in combination, a source of supply for the extinguishing medium normally maintained under non-delivery pressure, connections between such source and a normally-inactive delivery terminal, means whereby said connections are normally maintained free from such medium in advance of fire conditions at such terminal and are rendered active for delivering the medium at such terminal in the presence of fire conditions, said means including mechanism for producing a predetermined fluid pressure in said connections, said fluid pressure being of less value than the delivery pressure of the medium, normally-inactive pump mechanism for the extinguishing medium, and control means for the pump mechanism operatively connected in said connections to normally maintain such pump mechanism inactive, said means being operative to inaugurate pump mechanism activity in the presence of material pressure reduction in the connections, and to maintain such activity by the pump mechanism operations. 90

25. In fire extinguishing systems and in combination, a storage reservoir forming a source of supply for the extinguishing medium normally maintained under non-delivery pressure, connections between such source and a normally-inactive delivery terminal, means whereby said connections are normally maintained free from such medium in advance of fire conditions at such terminal and are rendered active for delivering the medium at such terminal in the presence of fire conditions, said means including fluid-pressure supply mechanism for automatically maintaining a predetermined pres- 100

sure in said connections, normally inactive pump mechanism for the extinguishing medium adapted to supplying said medium directly from the source to the connections and 5 rendered active by material pressure reduction in the connections, and means controlled by pressure variations in the connections for controlling mechanism operations.

26. In fire extinguishing systems and in 10 combination, a source of supply for the extinguishing medium, connections between such source and a normally-inactive delivery terminal, means whereby said connections are normally maintained free from such 15 medium in advance of fire conditions at such terminal and are rendered active for delivering the medium at such terminal in the presence of fire conditions, said means including normally-inactive pump mechanism 20 for the extinguishing medium operative in said connections, fluid pressure supply mechanism for producing a predetermined pressure in the connections during pump mechanism inactivity, said supply mechanism including a delivery line leading to the 25 connections between the pump mechanism and the source of medium supply.

27. In fire extinguishing systems and in 30 combination, a source of supply for the extinguishing medium, connections between such source and a normally-inactive delivery terminal, means whereby said connections are normally maintained free from such medium in advance of fire conditions at 35 such terminal and are rendered active for delivering the medium at such terminal in the presence of fire conditions, said means including fluid pressure supply mechanism for automatically providing a predetermined pressure in the connections, normally-inactive pump mechanism for the extinguishing medium and operative to produce a pressure of superior value in the connections, and control means within the supply 40 mechanism adapted to render the supply mechanism inactive in the presence of such superior pressure.

28. In fire extinguishing systems and in 50 combination, a storage reservoir forming a source of supply for the extinguishing medium normally maintained under non-delivery pressure, connections between such source and a normally inactive delivery terminal, means whereby said connections are 55 normally maintained free from such medium in advance of fire conditions at such terminal and are rendered active for delivering the medium at such terminal in the presence of fire conditions, said means including 60 fluid pressure supply mechanism having a supply line leading to said connections, said mechanism being adapted to automatically maintain a predetermined pressure in the connections, said supply line having a cross 65 sectional area less than the similar area of

the connections, normally inactive pump mechanism for the extinguishing medium, and means at the delivery terminal for opening the connections in the presence of fire conditions, whereby the fluid discharge from 70 the connections will be superior to its supply to produce a rapid pressure reduction, such pressure reduction being operative to render the pump mechanism active to deliver the medium directly to the connections under 75 delivery pressure, the pump mechanism being inactive except under fire conditions at the delivery terminal.

29. In fire-extinguishing systems adapted to be operative at either of a plurality of 80 points of application, and in combination, a source of supply for the extinguishing medium, main and branch line delivery connections between said source and normally-inactive individual delivery terminals, and 85 means whereby said connections are normally maintained free from such medium and for delivering the medium to an individual branch line and its delivery terminal selectively made active by the presence of fire 90 conditions at such terminal while maintaining the normal condition of the remaining branch lines, said means including control mechanism for each branch line operative to normally maintain communication 95 between the main and branch lines and close communication between such lines in the presence of fire conditions at a branch-line terminal other than that reached by the line being closed. 100

30. In fire-extinguishing systems adapted to be operative at either of a plurality of points of application, and in combination, a source of supply for the extinguishing medium, main and branch line delivery connections between said source and normally-inactive individual delivery terminals, and 105 means whereby said connections are normally maintained free from such medium and for delivering the medium to an individual branch line and its delivery terminal selectively made active by the presence of fire conditions at such terminal while maintaining the normal condition of the remaining branch lines, said means including control mechanism for each branch line operative to normally maintain communication between the main and branch lines by a restricted passageway and to produce complete communication between the main and that 110 branch line having the active terminal.

31. In fire-extinguishing systems adapted to be operative at either of a plurality of points of application, and in combination, a source of supply for the extinguishing medium, main and branch line delivery connections between said source and normally-inactive individual delivery terminals, and 125 means whereby said connections are normally maintained free from such medium 130

and for delivering the medium to an individual branch line and its delivery terminal selectively made active by the presence of fire conditions at such terminal, said means including control mechanism for each branch line operative to normally maintain restricted communication between the main and branch lines and to isolate the branch line or to increase communication between the main and branch lines in the presence of fire conditions.

32. In fire-extinguishing systems adapted to be operative at either of a plurality of points of application, and in combination, a source of supply for the extinguishing medium, main and branch line delivery connections between said source and normally-inactive individual delivery terminals, and means whereby said connections are normally maintained free from such medium and for delivering the medium to an individual branch line and its delivery terminal selectively made active by the presence of fire conditions at such terminal, said means including control mechanism for each branch line operative to normally maintain restricted communication between the main and branch lines and to isolate the branch line in the presence of fire conditions at a point of application remote from the delivery terminal of such branch line.

33. In fire-extinguishing systems adapted to be operative at either of a plurality of points of application, and in combination, a source of supply for the extinguishing medium, main and branch line delivery connections between said source and normally-inactive individual delivery terminals, and means whereby said connections are normally maintained free from such medium and for delivering the medium to an individual branch line and its delivery terminal selectively made active by the presence of fire conditions at such terminal, said means including fluid-pressure supply mechanism for providing fluid pressure in said connections, and control mechanism for each branch line, each control mechanism including a normally-closed valve operative in the branch line and a passageway by-passing said valve and normally permitting fluid pressure communication between opposite sides of the valve, and means controlled by the pressure in said passageway for controlling valve movements.

34. In fire-extinguishing systems adapted to be operative at either of a plurality of points of application, and in combination, a source of supply for the extinguishing medium, main and branch line delivery connections between said source and normally-inactive individual delivery terminals, and means whereby said connections are normally maintained free from such medium and for delivering the medium to an individual branch line and its delivery terminal selectively made active by the presence of fire conditions at such terminal, said means including control mechanism for each branch line operative to normally maintain restricted communication between the main and branch lines through a by-pass, and valve devices positioned in the by-pass at spaced-apart points.

35. In fire-extinguishing systems adapted to be operative at either of a plurality of points of application, and in combination, a source of supply for the extinguishing medium, main and branch line delivery connections between said source and normally-inactive individual delivery terminals, and means whereby said connections are normally maintained free from such medium and for delivering the medium to an individual branch line and its delivery terminal selectively made active by the presence of fire conditions at such terminal, said means including fluid-pressure supply mechanism for providing fluid pressure in said connections, and control mechanism for each branch line, each control mechanism including a normally-closed valve operative in the branch line and a passageway by-passing said valve and normally permitting fluid pressure communication between opposite sides of the valve, means controlled by the pressure in said passageway for controlling valve movements, and means for controlling said passageway.

36. In fire-extinguishing systems adapted to be operative at either of a plurality of points of application, and in combination, a source of supply for the extinguishing medium, main and branch line delivery connections between said source and normally-inactive individual delivery terminals, and means whereby said connections are normally maintained free from such medium and for delivering the medium to an individual branch line and its delivery terminal selectively made active by the presence of fire conditions at such terminal, said means including fluid-pressure supply mechanism for providing fluid pressure in said connections, and control mechanism for each branch line, each control mechanism including a normally-closed valve operative in the branch line and a passageway by-passing said valve and normally permitting fluid pressure communication between opposite sides of the valve, devices operative at spaced-apart points of the passageway for controlling it, and means operative intermediate said device operative points and controlled by the passageway pressure for controlling valve movements.

37. In fire-extinguishing systems adapted to be operative at either of a plurality of points of application, and in combination, a source of supply for the extinguishing medium, main and branch line delivery connections between said source and normally-inactive individual delivery terminals, and means whereby said connections are normally maintained free from such medium and for delivering the medium to an individual branch line and its delivery terminal selectively made active by the presence of fire conditions at such terminal, said means including control mechanism for each branch line operative to normally maintain restricted communication between the main and branch lines through a by-pass, and valve devices positioned in the by-pass at spaced-apart points.

38. In fire-extinguishing systems adapted to be operative at either of a plurality of points of application, and in combination, a source of supply for the extinguishing me-

- 5 medium, main and branch line delivery connections between said source and normally-inactive individual delivery terminals, and means whereby said connections are normally maintained free from such medium and for delivering the medium to an individual branch line and its delivery terminal selectively made active by the presence of fire conditions at such terminal, said means
- 10 including control mechanism for each branch line operative to normally maintain restricted communication between the main and branch lines through a by-pass, and valve devices positioned in the by-pass at spaced-apart points, one of said devices having its maximum port area less than the similar area of the other device.
- 15 38. In fire-extinguishing systems adapted to be operative at either of a plurality of points of application, and in combination, a source of supply for the extinguishing medium, main and branch line delivery connections between said source and normally-inactive individual delivery terminals, and means whereby said connections are normally maintained free from such medium and for delivering the medium to an individual branch line and its delivery terminal selectively made active by the presence of fire conditions at such terminal, said means
- 20 including fluid-pressure supply means adapted to normally maintain a substantially uniform fluid pressure in the system, and control mechanism for each branch line operative to maintain restricted communication between main and branch lines through a by-pass, said mechanism including valve devices in said by-pass adapted to maintain communication under fluid pressure variations in supply and prevent communication therethrough during delivery-pressures of the medium.
- 25 39. In fire-extinguishing systems adapted to be operative at either of a plurality of points of application, and in combination, a source of supply for the extinguishing medium, main and branch line delivery connections between said source and normally-inactive individual delivery terminals, and means whereby said connections are normally maintained free from such medium and for delivering the medium to an individual branch line and its delivery terminal selectively made active by the presence of fire conditions at such terminal, said means
- 30 including control mechanism for each branch line operative to normally maintain restricted communication between the main and branch lines through a by-pass, and valve devices positioned in the by-pass at spaced-apart points, said devices differing in maximum port area, one of said devices having means to prevent closing of the passageway therethrough during pressure variations below a predetermined approximate value.
